Thrashing and Grinding Machine.

Patented Dec. 11, 1832.

The subscriber referred to in these Letters Patents, and making part of the same, containing a description in the words of the said subscriber himself of his improvement in the Machine for threshing grain, chipping corn & grinding Apples.

To all to whom these presents shall come. Be it known that I, John Brewer, of New Preston, in the County of Dutchess, State of New York, have invented a new and useful improvement in the machine for threshing wheat & all other kinds of grain & seed, & for the chipping of corn and grinding Apples; and that the following is a full and exact description of the construction & operation of the said Machine as invented or improved by me.

This machine is constructed by a frame of wood of a size to suit the power to be applied, but a size suitable to be driven by two horses, etc, two feet six inches wide, about 3 feet long, & from 18 feet to 30 inches high with a cylinder of iron or wood long enough to fill the width of the frame, with bars of iron from one and a half to two inches wide, & about three eighths of an inch thick, these bars are to be let edgeways into the cylinder about half the width of the bar & the outer edge chamfered down on one side to the thickness of one eighth of an inch thick, with the surface of the bars smooth or toothed, about like hand saw teeth, these bars to be placed on the cylinder from five to seven inches apart round the surface of the cylinder, & between each two bars two straight rows of iron spikes, driven fastened into the cylinder from one end to the other, from two to three inches apart in each row, & the rows about one inch apart: the spikes in the second row to stand opposite to the space of the first, & so on interchangeably round the surface of the cylinder; the spikes may be round or square, & from one fourth to three eighths of an inch in diameter, & must extend about a quarter of an inch from the surface of the cylinder as the bars on the cylinder; the size of the cylinder must be proportioned to the velocity to be given.

A timber inch cylinder should be arranged to give about two revolutions in a minute; a bottom or frame for a number of iron bars, on which upright square bars of iron from five eighths to a three

so that the open side is diameter, or flat bars set up edge ways from the back to the middle part, beginning about as high as the center of the cylinder, & going under the bottom of it, about one-fourth way round, & far enough down the grain to be thrashed, with from two to four straight rows of concave bars, spikes to be drove or fastened between each two concave bars; the spikes in each row about three-fourths of an inch from each other, and each two rows to be about the same distance apart. The spikes in the concave may be about the same size of the spikes in the cylinder. If the spikes in the cylinder or concave are of large size, the outer ends may be nicely sharp, those in the concave may extend about as high as the surface of the concave bars, & the spikes in each second row to stand opposite the open in the first; the cylinder being suspended by friction or plain boxes so as to raise it from or let it near the concave as occasion may require by means of nuts & screws; the concave may be stationary, or may be constructed as to spring down when hard pressed from one-fourth to a half an inch.

An inclined plane or box is placed on the back part of the frame the forward part of which comes close to the first bar of the concave, to conduct the grain or corn in between the cylinder & concave.

The shaft of the cylinder extends thro' side of the frame far enough to admit of a small wheel made fast to apply a band from a drum or wheel to put the machine in motion. The grain is drawn in by the bars & spikes on the cylinder over the surface of the concave bars, & over and between the spikes in the concave.

A machine for grinding apples may be of a size to suit the power to be applied, but a size suitable to be drove by one horse, may be from one to two-thirds as wide as the machine above described with the last spike of the cylinder & concave extending about half as far from the surface of the cylinder & concave as described in the above machine. With the machine for apples or corn round, & a large high plane on the cylinder so as to conduct the apples in between the cylinder & concave. What is claimed by this improvement, is the last spike of the cylinder, acting upon the grain, over the concave bars.
